(57) **CLAIM**

The ornamental design for a hanging clip as shown and described.

DESCRIPTION

FIG. 1 is a front perspective view of a hanging clip showing my new design;

FIG. 2 is a front perspective view of the hanging clip thereof;
FIG. 3 is an exploded front perspective view of the hanging clip thereof;

FIG. 4 is a front elevational view of the hanging clip thereof;
FIG. 5 is a rear elevational view of the hanging clip thereof;

FIG. 6 is a top plan view of the hanging clip thereof;
FIG. 7 is a bottom plan view of the hanging clip thereof;
FIG. 8 is a left elevational view of the hanging clip thereof;
FIG. 9 is a right elevational view of the hanging clip thereof;
and,

FIG. 10 is a bottom plan view of the top piece of the hanging clip thereof, shown isolated from the bottom piece for clarity.

The broken lines in FIG. 2 depict an environmental wig that forms no part of the claimed design. The broken lines in FIGS. 3 and 10 depict portions of the hanging clip that form no part of the claimed design.

1 Claim, 7 Drawing Sheets
